[57] CLAIM

The ornamental design for a combined carpenter's pencil and ruler, as shown and described.

DESCRIPTION

FIG. 1 is a perspective view of a combined carpenter's pencil and ruler showing a first embodiment of my invention;

FIG. 2 is a front elevational view thereof;

FIG. 3 is a rear elevational view thereof;

FIG. 4 is a left end elevational view thereof;

FIG. 5 is a right end elevational view thereof;

FIG. 6 is a top plan view of FIG. 1;

FIG. 7 is a bottom plan view of FIG. 1;

FIG. 8 is a rear elevational view of a combined carpenter's pencil and ruler of a second embodiment of my new design; the front elevational view, the left end elevational view, the right end elevational view, the top plan view and the bottom plan view are mirror images of FIG. 2, FIG. 4, FIG. 5, FIG. 6 and FIG. 7, respectively;

FIG. 9 is a perspective view of a combined carpenter's pencil and ruler showing a third embodiment of my new design;

FIG. 10 is a front elevational view of FIG. 9;

FIG. 11 is a rear elevational view of FIG. 9;

FIG. 12 is a left end elevational view of FIG. 9;

FIG. 13 is right end elevational view of FIG. 9;

FIG. 14 is a top plan view of FIG. 9;

FIG. 15 is a bottom plan view of FIG. 9; and,

FIG. 16 is a rear elevational view of a combined carpenter's pencil and ruler of a fourth embodiment of my new design; the front elevational view, the left end elevational view, the right end elevational view, the top plan view and the bottom plan view are mirror images of FIG. 10, FIG. 12, FIG. 13, FIG. 14 and FIG. 15, respectively.
